UNITED STATES PATENT OFFICE

135,664

DESIGN FOR A BOOK HOLDER

Willard L. Pollard, Evanston, Ill.

Application August 20, 1942, Serial No. 107,978

Term of patent 3½ years

To all whom it may concern:

Be it known that I, Willard L. Pollard, a citizen of the United States, residing at Evanston, in the county of Cook and State of Illinois, have invented a new, original, and ornamental Design for a Book Holder, of which the following is a specification, reference being had to the accompanying drawing, forming a part thereof.

The figure is a perspective view of a book holder, showing my design.

I claim:

The ornamental design for a book holder, substantially as shown.

WILLARD L. POLLARD.
